UNITED STATES PATENT OFFICE

1,998,311

DISPENSING APPARATUS

Earl E. Eickmeyer and George W. Eichhoff, Dayton, Ohio, assignors to The Dayton Pump & Mfg. Company, Dayton, Ohio, a corporation of Ohio

Application July 28, 1932, Serial No. 625,426

3 Claims. (Cl. 312—117)

Our invention relates to dispensing apparatus.

It is the object of our invention to provide a combined apparatus for dispensing of liquids in bulk, liquids in small amounts and to dispense other articles while maintaining the temperature of such articles at the desired point.

It is our object to provide such dispensing means accessible to the occupants of an automobile so that the occupants may view the articles to be purchased while seated in the automobile during the period the car is being filled with oil and gasoline dispensed from our apparatus.

It is a further object to provide a cabinet in which the liquid dispensing apparatus protects and supports the frame and glass panels constituting the doors of the cabinet for dispensing bottled goods, such as oil, liquid refreshments, and the like.

It is our object to provide in this combination means for cooling the contents of this cabinet for summer and heating them in the winter.

Referring to the drawings:

Figure 1 is a front elevation;

Figure 2 is a vertical section;

Figure 3 is a detail section through one wall of the cabinet;

Figure 4 is a section on the line 4—4 of Figure 2;

Figure 5 is a view similar to Figure 3 showing the arrangement of the opposite side of the cabinet wall.

Referring to the drawings in detail, 1 represents the foundation or the ground. Upon this foundation are mounted suitable pump casings having bases 2, vertical columns 3, caps 4 and illuminated display signs 5. These several parts together constitute the pump casing. In the view shown there are three of such pump casings. There may be one or more.

Interposed between and supported by the pump casings is a dispensing cabinet comprising end walls 6 and 7 between which are mounted trays 8, 9 and 10. The tray 10 may have a completely closed surface on one side over the compressor 11 and a foraminous body as at 12 on the other side so that the air from the fan 13 in the compartment 14 may circulate through the compartment 15 and the compartment 16 when the platform 9 is also a mesh work to permit of the circulation of air. Both the fan 13 and compressor 11 are mounted upon the base plate 17. The side walls 6 and 7 are embraced between the bases 2 of the pump casings and are held in position thereby. The tops of these side walls 6 and 7

are held in position by the braces 18 located between the tops of the side walls 6 and 7 and the tops of the casings 3 for the pumps.

On top of the pump casings and enclosing the top of the dispensing cabinet formed by the side walls 6 and 7 is a cover plate 19 having a decorative cover 20. This decorative cover may be supported on the cap members 4 either by welding, bolting or by suitable brackets 21. The cover 19 forms the top of a tire cabinet 22 in the dispensing cabinet for the tire 23 which can be seen through the glass doors 24 having the frames 25 which are hinged to a cover plate 26 which forms one side of the decorative frame on the outside wall of the cabinet. A similar strip 27 is provided to provide a door jamb on the other side of the cabinet. On the side of the cabinet is mounted at the base a base plate 28 of decorative character and a plurality of spaced transverse door jamb members 29. Swinging doors 30 are provided for enclosing the several compartments 14, 15 and 16. Within these compartments refrigeration may be supplied from the compressor 11 by the coils 31. The air circulating through the compartments will circulate over these coils and provide means for maintaining food products in a proper condition for dispensing to the motorists along side of the dispensing apparatus, which is the subject of this invention, at the same time he is receiving his gasoline from one of the pump structures enclosed within the housing 3.

The dial of the pump structure is indicated at 32 and the dispensing hose at 33 controlled by the dispensing valve 34.

Turning to Figures 3, 4 and 5, where the details of the cabinet are more clearly disclosed, it will be noted that between the side walls 6 and 7 there are mounted transverse angle iron members 35 which serve to support the floor plates or separators 8, 9 and 10 in conjunction with angle irons 36 running fore and aft along the side walls 6 and 7.

The base plate 28 is adapted at 28a to overlap the angle iron 35 while the partition member 45 overlaps at 10a the vertical portion of the angle iron 35. Thus is formed a door jamb over the strip 29 which forms a part of the door. The glass is designated 29a and is held within the frame 30. The door may be hinged at its end on 50 the side frames 27.

By this arrangement, a neat, smooth surface of nickel-plated or chromium-plated door frames 30 carrying the glass 29a is provided. The contents of the cabinets thus formed can be readily

seen by the motorist seated in his car along side of the cabinet suggesting to him the purchases that he can or should make.

On the other side, the cabinet of similar construction is provided with a combined fan 13 and a heating element 13a for circulating heated air throughout the compartments 15 and 16 in order to prevent the contents from freezing during winter and to preserve the bottles of lubricating oil and grease at a proper temperature for immediate application to the automobiles receiving supplies at the station.

It should be particularly noted that the casings 3 act as enclosing and positioning barriers for protecting and aligning dispensing cabinets, that the cabinets have doors on one or both sides, preferably the latter, and that the overlapping cap plate 9 with the spacer members 18 ties the cabinets into position between the vertical casings 3 of the pumps.

The cabinet structure broadly consists of end plates, such as 6 and 7, having angle iron shelf members 36 connected at their free ends by the angle iron members 35, in the angles of which the vertical face plates, such as 28, and the shelves 8, 9 and 10 have their turned-over ends mounted. This also forms an angular abutting surface for the swinging free edge of the door of the cabinet.

Although we use thin sheet metal of light weight and of minimum strength, relatively heavy door frames and plate glass doors may be employed and safely operated, and, at the same time, the light sheets used for the cabinet may be used without the sacrifice of adequate strength.

It will be noted that some of the members 35 are T-shaped as at 35a in order to accommodate the top of one door and the bottom of the other door, but the principle remains the same. By this arrangement doors with flush faces can be employed.

It will be noted that we desire to comprehend

within our invention such modifications as may be necessary to adapt it to varying conditions and uses.

Having thus fully described our invention, what we claim as new and desire to secure by Letters Patent, is:

1. In combination, a pair of spaced dispensing pump casings, a dispensing cabinet embraced therebetween, a cover therefor overlapping the top of said cabinet to close it and overlapping the tops of the pump casings, and cap members on said pump casings adapted to embrace and support the ends of said cover.

2. In combination, a pair of spaced casings for liquid dispensing pumps comprising a base casing, a pump casing and a capital casing, a dispensing cabinet therebetween having end walls, the bottoms of which engage the base casings and the tops of which are spaced from the tops of the pump casings, spacer members therebetween, a common overlapping cap member enclosing the top of the dispensing cabinet formed by said end walls and part of the tops of the pump casings engaging the sides of the capital casings, a plurality of shelves in said dispensing casings between the end walls and swinging doors therefor.

3. In a dispensing cabinet, dispensing pump casings forming end walls, angle iron shelf supporting members on said walls, shelves of sheet material on the supporting members, angle iron members connecting said end walls to one another forming supports for said shelves, and abutments for swinging doors and swinging doors pivoted on one of the casings so formed to form front and rear walls thereof, and a cap member mounted on the top angle iron members extending between the end walls.

EARL E. EICKMEYER.
GEORGE W. EICHOFF.
